UNITED STATES PATENT OFFICE.

WILLIAM G. HAY, OF MANCHESTER, LANCASTER, ENGLAND.

ROTARY FLUID COMPRESSOR, EXHAUSTER, MOVER, OR ENGINE.

1,367,256.

Specification of Letters Patent.

Patented Feb. 1, 1921.

Application filed October 25, 1919. Serial No. 333,146.

To all whom it may concern:

Be it known that I, WILLIAM GEORGE HAY, a subject of the King of Great Britain, residing at Manchester, in the county of Lancaster, England, have invented certain useful Improvements Relating to Rotary Fluid Compressors, Exhausters, Movers, or Engines, of which the following is a specification.

10 This invention relates to rotary fluid compressors, exhausters, movers or engines generally of the type wherein a rotor is mounted eccentrically in a stationary casing and vanes are provided adapted to move relatively to the rotor, and is more particularly applicable to rotary blowers or air compressors, exhausters or movers.

The main object of my invention is to increase the efficiency of compressors, exhausters, movers or engines of said type by adapting them to run at much greater speeds than hitherto, without occasioning friction and wear between the vanes and the casing. Another object is to increase the smoothness 25 of running and reduce vibration to a minimum. A third object is to facilitate manufacture of such compressors, exhausters or movers and to render it possible to readily lubricate all moving parts, thereby reducing 30 friction generally. A further object is to provide a construction in which the efficiency of the parts remains unaffected by the action of solid matter drawn in a state of suspension into the machine.

35 According to my invention, in a rotary fluid compressor, exhauster, mover or engine of the specified type, the vanes are oscillatably or slidably mounted in the rotor and are so formed and connected to connecting rods 40 rotatable about the axis of the casing that a constantly equal, predetermined clearance is obtained between the cylinder and the vane surfaces co-acting therewith to form a partial or complete seal, in all positions 45 of the vanes.

The rotor is formed hollow and the vanes are constructed hollow with open inner ends, the connecting rods being situated in the chamber formed by the rotor and vanes.

50 In order to balance the vanes and connecting rods, counter weights may in some cases be mounted to oscillate about the rotor axis and be operatively connected to the vanes in such a manner that movement of the vanes 55 away from the rotor axis, causes the counter weights to move to the opposite side of the

axis and thereby balance the centrifugal action exerted on the connecting rods and vanes.

I attain the recited objects by the mechanism illustrated in the accompanying two sheets of drawings.

Figure 1 is a view in vertical section on line 1-1 of Fig. 2 and

Fig. 2 is a view in vertical section through the axis of the machine, the two figures illustrating one construction.

Fig. 3 is a view in vertical section on line 3-3 of Fig. 4 and

Fig. 4 is a view in vertical section on line 4-4 of Fig. 3 looking in the direction of the arrow, and illustrate a second construction.

Similar letters and numerals refer to similar parts throughout the several views.

In the construction illustrated in Figs. 1 and 2 of the drawings, which is particularly adapted to deal with clean or dust free air, the rotor *a* is formed hollow and with radially disposed slots *b* containing sliding vanes *c*. Each vane *c* is of rectangular cross section and is made a sliding fit in its slot and of box formation with its inner end open to the interior of the hollow rotor. One end of a connecting rod *d* extends into each hollow vane and is oscillatably connected thereto at *e* near its outer end, preferably by a ball bearing as shown. The axis *e* of oscillation of the connecting rod is parallel with the rotor or cylinder axis and the surface of the vane *c* which co-operates with the cylinder periphery is formed concentric with the axis *e* of oscillation. The other end of each connecting rod *d* is rotatably mounted, preferably by means of a ball bearing as shown, on a stationary stud or spindle *f* secured concentrically to the machine casing *g* and projecting into the hollow rotor *a* through an aperture *h* formed in one side thereof. There are thus two connecting rods *d*, both connected to the stationary spindle *f* and each connected to one of the sliding vanes *c*. The rotor *a* may be mounted to rotate on a ball bearing or bearings *i* and *j* arranged at the opposite side of the casing *g*.

It will be appreciated in the above described construction, that the vanes *c*, although slideable in the rotor *a*, are held by the connecting rods *d* with their points of connection (*e*) with such rods at a fixed distance from the center of the casing *g*, and that the working surfaces of the vanes *c* are everywhere equidistant from said points of

connection, with the result that the part of the working surface momentarily coöperating with the cylinder g always clears the cylinder g by a constant distance which can be 5 fixed by suitably proportioning the connecting rods d .

The bearings of the inner ends of the connecting rods d may be readily lubricated by providing the fixed stud or spindle f 10 with a passage k or grease tube through which grease can be injected from the exterior of the casing g . The sliding vanes c may be lubricated by forming overhung annular ribs l on the sides of the rotor a and 15 providing passages m in the casing g from the exterior to parts inside the casing g where the overhung ribs l can catch lubricant falling therefrom. Passages n are provided which lead from the overhung inner 20 periphery of the ribs l to annular grooves o leading to the inner ends of the slots b containing the vanes c . The connecting rods d may be provided with passages p or tubes to conduct to the outer ends thereof a portion 25 of the grease injected through the stationary stud or spindle f .

In the construction of blower illustrated in Figs. 3 and 4 and more particularly adapted for dealing with dust or the like 30 laden air, the rotor a is again hollow and provided with slots b which communicate with hollow interior thereof. Each vane c' is of box formation with its interior open to the hollow interior of the rotor a and is oscillatably mounted at q , q in one of the rotor 35 slots b , the axis of oscillation being parallel with the axis of the cylinder g or rotor a . A connecting rod d' projects into the vane c' and is oscillatably connected to the same 40 near its outer end at r , the axis of oscillation again being parallel with the axis of the cylinder g or rotor a . The part s of the vane surface which coöperates with the periphery of the cylinder g is situated in proximity to the connecting rod d' and is concentric with the axis r of oscillation of such rod. This surface is continued inward, the continuation t being concentric with the axis q of oscillation of the vane c' and in sliding 45 contact with one side of its slot b . The surface is continued in the direction of the axis q of oscillation of the vane, and is prolonged inwardly, the prolongation u being concentric with the axis q and forming a sliding fit 50 with the other side of its slot b . This surface is completed to form the vane by two parallel walls v which are in sliding contact with the remaining two sides of the slot b and the sides of the casing g . The connecting rods d' are rotatably mounted, preferably by means of ball bearings as shown, 55 on a stud w concentric with the cylinder casing g and situated inside the rotor a . In order to insure a tight joint between the 60 ends of the vanes c' and the rotor a , the re-

spective sides of the slot b have white metal x or the like cast into suitable undercut slots therein for the ends of the vanes c' to slide on.

The stud w on which the connecting rods d' rotate may form part of a crank y on the end of a stationary shaft z secured to the casing g concentric with the rotor a , and partially supported by a ball bearing 5 on the rotor a . 75

For the purpose of balancing the parts described with reference to the second construction, I may employ the following device, but it will be appreciated that such device is not essential in all cases:— 80

At a point intermediate between each connecting rod d' and vane axis q , I connect one end of a link 6 to each vane, and connect the other end thereof to one arm of a lever 7 oscillatably mounted on a stud 8 or spindle concentric with the axis of the rotor a . The other arm of the lever 7 carries a counter weight 18 . In operation, the outward or inward movement of the vane c' on one side of the axis of the rotor a produces a corresponding movement of the counter weight 8 90 at the other side of said axis, the forces set up by centrifugal action on the vane c' and parts moving therewith being thereby counter balanced by the forces set up by such action on the counter weight 18 , which of course act in opposite direction to the first named forces. 95

All the moving parts described with reference to the second named construction may 100 be lubricated by forming suitable passages 11 in the casing g , and a passage 12 in fixed shaft z , and cranked stud y , w , and providing lubricator tubes 9 to the outer ends of the connecting rods d' , the inlet ends of the 105 tubes being led to the sides of the rotor a where lubricant can be injected through a passage 10 provided therein.

I claim:

1. A rotary fluid compressor, exhauster, 110 mover or engine, comprising in combination, a cylindrical casing; a hollow cylindrical rotor eccentrically mounted therein; vane slots in said rotor; hollow vanes movable in said slots; means mounted co-axial with 115 said casing to project into the interior of the hollow rotor and form a rigid axis; and members connecting the hollow vanes to said means; and working surfaces on the hollow vanes concentric with the point of connection of said members to said vanes. 120

2. A rotary fluid compressor, exhauster, mover or engine, comprising in combination, a cylindrical casing; a hollow cylindrical rotor eccentrically mounted therein; vane 125 slots in said rotor extending from the interior to the exterior thereof; hollow vanes movably mounted in said slots with open ends communicating with the interior of the rotor; a stud rigidly connected to the cylin- 130

- drical casing co-axial with said casing; a plurality of connecting rods all rotatably mounted at one end on said stud and each extending into and oscillatably connected to the interior of one hollow vane; and working surfaces on said vanes, all parts of which are radially equi-distant from the line of connection of the respective vane with its connecting rod.
5. A rotary fluid compressor, exhauster, mover or engine, comprising in combination, a cylindrical casing; a rotor eccentrically mounted therein; vane slots in said rotor; vanes movable in said slots; a member mounted co-axially with the cylindrical casing; means connecting said vanes to said member; a member arranged co-axially with the rotor; and counter weights revoluble on the last named member and linked to said 15 vanes; said counter weights being adapted to set up centrifugal forces substantially equal to but oppositely directed to those set up by said vanes.
4. A rotary fluid compressor, exhauster, mover or engine, comprising in combination a cylindrical casing; a hollow rotor eccentrically mounted therein; movable vanes on said rotor; a stationary stud on said cylindrical casing; ball bearings on said stud; connecting rods mounted on said ball bearings; a ball bearing on each vane connecting each connecting rod to one vane; means on said stud for conveying lubricant to the ball bearing on each vane for conveying lubricant thereto; and means on said casing and rotor for lubricating said movable vanes.
5. A rotary fluid compressor, exhauster, mover or engine, comprising in combination, a cylindrical casing; a hollow rotor eccentrically mounted therein; slots in said rotor; a member entering from one side; vanes oscillatably mounted in said rotor; surfaces on said vanes concentric with the points of oscillation and in sliding contact with opposite sides of said slots; renewable wearing surfaces in said slots; surfaces on said vanes in sliding contact with the opposite remaining sides of said slots; members connecting said vanes with the cranked part of said shaft, and working surfaces on said vanes concentric with the points of connection of said members with said vanes.
6. A rotary fluid compressor, exhauster, mover or engine, comprising in combination a cylindrical casing; a hollow rotor eccentrically mounted therein, hollow vanes oscillatably mounted on said rotor and means within said rotor retaining the working surfaces of said vanes a constant, predetermined distance from the working periphery of said cylinder in all working positions of said vanes.
7. A rotary fluid compressor, exhauster, mover or engine, comprising in combination, a cylindrical casing; ball bearings provided on said casing in eccentric relation thereto; a rotor mounted on said ball bearings; an internal boss on said rotor; a ball bearing in said boss; a shaft fixed to said casing and partially supported by said ball bearing; slots in said rotor; ball bearings in said slots; hollow vanes mounted on said ball bearings; ball bearings on said vanes; a cranked stud on said shaft; ball bearings on said stud; and connecting rods mounted on the ball bearings on the vanes and on the ball bearings on said stud, thereby connecting said vanes to said stud.

Signed at Manchester, in the county of Lancaster, this 6th day of October, 1919.
